UNITED STATES PATENT OFFICE.

JOSA TORYOWSKI, OF SOUTH ST. PAUL, MINNESOTA.

RAILROAD-SWITCH.

1,340,992.

Specification of Letters Patent.

Patented May 25, 1920.

Application filed December 18, 1919. Serial No. 345,896.

To all whom it may concern:

Be it known that I, JOSA TORYOWSKI, a citizen of Austria, residing at South St. Paul, in the county of Dakota and State of Minnesota, have invented certain new and useful Improvements in Railroad-Switches, of which the following is a specification, reference being therein to the accompanying drawing.

10 The invention relates to railroad switches and has for its object to provide a temporary switch which may be easily and quickly moved from place to place and so disposed and connected between parallel tracks, 15 whereby a train or car on one of said tracks may be switched to the adjacent track.

A further object is to form the switch member from rails of the conventional type and to cut away the flanges and web of 20 the rail so that the rails will engage the inner rails of the adjacent parallel tracks, thereby allowing the treads of the rails forming the temporary switch to be disposed over the treads of the permanent track rails 25 and terminate in registration with the treads of the permanent rails, also to provide bracing means adapted to arch over the adjacent inner rails of the permanent tracks, thereby maintaining the rails forming the 30 temporary switch in their proper spaced relation to each other.

With the above and other objects in view the invention resides in the combination and arrangement of parts as hereinafter set 35 forth, shown in the drawings described and claimed, it being understood that changes in the precise embodiment of the invention may be made within the scope of what is claimed without departing from the spirit of 40 the invention.

In the drawings:—

Figure 1 is a plain view of a road bed showing parallel tracks and the temporary switch applied thereto.

45 Fig. 2 is a perspective view of the switch showing the same detached.

Referring to the drawings, the numerals 1 and 2 designate parallel tracks and 3 the temporary switch. Temporary switch 3 is 50 formed from a pair of rails 4, which rails are adapted to arch the space between the tracks so that a train or car may be moved from one track to the other. Rails 4 have their flanges and webs cut away as at 5 for 55 the reception of rails 1^a and 2^a of the permanent track thereby leaving the tread por-

tions 6 above rails 1^a and 2^a of the permanent track so that the wheel flanges of the train can pass over the treads 1^a and 2^a. The ends of the rails 4 are curved as at 7 and 60 have their flange and web portions cut away as at 8, allowing the tread portion 7 to be disposed over the tread portions of the rails of the permanent tracks so that the wheels of the cars will be guided by the tread 7 65 so that the flanges of the wheels will run off the ends of the temporary switch, in such a manner that the flanges of the wheels will engage the inner sides of the treads of the permanent rails. To prevent the spreading 70 of the ends 9, said ends are provided with angle brackets 10 which extend outwardly and downwardly and are adapted to be spiked to the cross ties thereby preventing spreading or springing of the ends 9. Rails 75 4 are held in spaced relation to each other by bars 11 and 12, which bars have their ends bent at right angles so as to form portions 13 which are in a vertical position. Portions 13 have extending outwardly there- 80 from threaded members 14 which pass through the webs of rails 4 and by means of nuts 15 the rails are maintained in spaced relation to each other. Bars 11 and 12 arch the permanent rails 1^a and 2^a, but it will be 85 seen that they terminate so that they will not interfere with the movement of the wheel flanges over the treads of the temporary switch. Pivoted as at 16 to the bars 12 are angle members 17 which extend 90 toward the ends of the switch and terminate in threaded members 17^a which members are adapted to be threaded through the rails 4 for additionally bracing the same and maintaining them in their relative parallel 95 positions.

When it is desired to move a train from one track to another the temporary switch is placed in the position shown in Fig. 1 and members 10 spiked to the ties, then the train 100 or car can be easily moved. It is to be understood that by making the central portion of the switch curved it will be possible to move cars from concentrically disposed tracks if so desired.

105 The invention having been set forth what is claimed as new and useful is:—

A temporary switch between parallel tracks, said temporary switch comprising a pair of rails, said rails being normally held 110 spaced from each other by arching members arching the adjacent rails on the inner sides

of the parallel tracks, cut away portions in the rails of the temporary switch for the reception of the adjacent inner rails of the permanent tracks, the ends of the rails of the temporary switch having the flanges and webs cut away so that the treads thereof will register with the treads of the rails of the permanent tracks and brackets carried by

the treads at the ends of the rails of the temporary switch and adapted to be secured to 10 the cross ties for preventing lateral springing or spreading of said tread portions.

In testimony whereof I heretinto affix my signature.

JOSA TORYOWSKI.
